UNITED STATES PATENT OFFICE

RAYMOND J. WEAN, OF WARREN, OHIO, ASSIGNOR TO THE WEAN ENGINEERING COMPANY, INC., OF WARREN, OHIO, A CORPORATION OF OHIO

FURNACE CONVEYER

Application filed October 6, 1930. Serial No. 482,555.

My invention relates to furnaces and, in particular, to conveyers for furnaces of the continuous heating type through which articles are adapted to be transported for heat treatment such as normalizing.

In normalizing metal articles, such as sheets, it has been the practice heretofore to provide a continuous heating furnace of appropriate length provided with a conveyer 10 for transporting the sheets through the heating zone of the furnace. It has been found necessary, in order to avoid injury to the sheets as the result of their contact with the supporting members of flights of the conveyers employed, to utilize so-called "waster" sheets. These waster sheets are simply pieces of thin gauge metal of appropriate size which are placed on the conveyer for supporting the sheet being transported to protect it from 20 direct contact with the conveyer flights.

The use of waster sheets is objectionable, principally for the reason that considerable labor is required to place them in position on the conveyer before charging the sheets to 25 be treated thereinto. It is also necessary to provide furnace attendants for removing the waster sheets at the discharge end of the furnace after the treated sheets have been taken from the conveyer. The waster sheets 30 are then returned to the charging end of the furnace where they are used over and over again. It is obvious that the amount of labor required for handling the waster sheets is very considerable. In fact, more 35 labor is required to handle the waster sheets than the finished sheets being treated.

I have invented a furnace conveyer which eliminates the large amount of labor necessary for treating sheets in a continuous furnace by the previous method. In accordance 40 with the invention, I provide a continuous heating furnace with a primary conveying means, such as a chain conveyer, having spaced flights. This conveyer may be of the type which has previously been used in such installations and which is described and illustrated in detail in my copending application, Serial No. 482,213, filed September 16, 1930, for continuous heating furnaces. A plural- 45 ity of such conveyer chains are generally em-

ployed, driven by a common driving mechanism, for transporting sheets through a furnace.

In order to protect the sheets being treated from injury resulting from direct contact with the flights of the conveyer chains, I provide continuous metallic strips or bands overlying the flights of the conveyer chains and traveling therewith to support the sheets. The principal driving force is applied to the 50 chains and only sufficient tension is imparted to the bands to insure their movement with the chains. Preferably, the bands are driven by the same driving mechanism which effects movement of the chains. The bands 55 may be of any suitable metallic composition to insure their satisfactory performance of the function required of them. Preferably, I employ bands of a heat-resistant alloy steel.

Since the bands are continuous from end to 70 end of the furnace, and are endless in the manner of a belt, the step of placing waster sheets in position on the chain conveyers is entirely eliminated and the desired protection from contact therewith is afforded by 75 the continuous waster bands or strips.

For a complete understanding of the invention, reference is made to the accompanying drawings illustrating the present preferred embodiment thereof.

Figures 1A and 1B illustrate a vertical, central section through a furnace having the conveyer of my invention applied thereto, certain parts being shown in diagram only;

Figures 2A and 2B constitute a horizontal 85 sectional view of the furnace;

Figure 3 is a detailed side view to an enlarged scale of the chain and flights constituting one of the chain conveyers; and

Figure 4 is a sectional view along the 90 line IV—IV of Figure 3.

Referring in detail to the drawing, the furnace comprises a chamber 10 open at the ends and having side, top, and bottom walls 11, 12, and 13. The walls of the furnace 95 are built of refractory brick in the well known manner and are enclosed within a structural frame work 14 supported on a suitable foundation 15.

Offset burner chambers 16 are let into the 100

side walls of the furnace and are provided with burners 17 and baffles 18. The burners 17 define the limits of the heating zone of the furnace adjacent the charging end thereof. Any suitable fuel supply system for the furnace may be provided. Adjacent the discharge end of the furnace, a series of transverse conduits 19 are provided which are connected to a pneumatic circulating system 20 carrying a cooling medium for controlling the temperature of the cooling zone thereby provided.

The means for conveying articles such as sheets through the furnace to subject them to the desired heat treatment, comprises a primary or main conveyer in the form of a plurality of chains 21 having bearing rolls 22 and supporting arms or flights 23 at spaced intervals therealong. In the embodiment illustrated, I show four chains 21. The chains 21 pass over driving sprockets 24 adjacent the discharge end of the furnace, the sprockets being keyed to a driving shaft 25 supported in suitable bearings 26. At the charging end of the furnace, the chains pass over idler sprockets 27 loosely mounted on a shaft 28. The shaft 28 is journaled in a shiftable frame 29 to which a bell crank 30 is secured having a counterweight 31 for maintaining the chains 21 taut. The rolls 22 ride on upper and lower guiding rails 32 of channel form for supporting the chains intermediate the driving idler sprockets. As is customary in this type of conveyer, the chains 21 pass through the furnace below the floor thereof, the flights 23 projecting upwardly through the slots in the floor.

In order to protect the sheets transported by the primary conveying means, constituted by the chains 21, from injury resulting from contact with the latter, I provide a continuous strip or band 33 for each chain. Each band is adapted to travel through the furnace with its chain, being supported thereby. The bands 33 travel over driving discs 34 keyed to a shaft 35 supported in bearings 36. Idler discs 37 are loosely mounted on a shaft at the discharge end of the furnace. The shaft 38 is preferably adjustably secured in the frame 50 or yoke 29 so that the counterweight 31 will be effective to maintain the bands 33 taut, as well as the chains 21. The lower run of each band 33 travels over supporting rollers 39 journaled in bearings 40 below the furnace. Pressure rolls 41 are mounted below the driving discs 34 and the idler discs 37 in housings 42. The rolls 41 are forced into engagement with the bands 33 by springs 43 and insure good frictional engagement between the bands and the discs to prevent relative slippage thereof.

The driving mechanism for the drive shaft 25 of the chain conveyers includes a motor 44, speed reduction gearing 45, and a chain and sprocket drive 46 connecting the latter to the

shaft 25. In order to insure simultaneous movement of the chains and bands, I prefer to positively drive the shaft 35 carrying the driving discs 34. This drive may conveniently be effected by means of a chain and sprocket connection 47 between the shafts 25 and 35. This drive should, however, be adjusted so that the main driving tension is applied to the chains and only sufficient force is exerted on the bands to insure their movement along with the chains.

The bands 33 may be of any suitable metallic composition, but I prefer to employ a steel band having any conventional carbon content or an alloy of steel and chromium or steel, chromium, and nickel, or any so-called heat-resistant alloy. The metal belt or strip may be made endless by welding, stitching, or seaming or may be of a one piece construction without joints.

In operation, the bands or strips 33 travel with the conveyer chains at the same speed. At the charging end of the furnace, the sheets to be treated are placed on the bands and are thereby protected from direct contact with the conveyer flights. At the discharge end of the furnace, the sheets are removed and the strips automatically returned to the charging end of the furnace. It will be apparent that the manual handling heretofore necessary with separate waster sheets is entirely done away with, and it is found that the number of furnace attendants can be practically cut in half. The bands 33 constitute a secondary conveying mechanism, cooperating with the primary conveyer in the form of the chains 21, although, as previously stated, the principal driving effort is applied through the chains and not through the bands.

Although I have illustrated and described herein but a single preferred embodiment of the invention, I do not intend to be limited to the specific details of this disclosure since the invention may be otherwise embodied without sacrificing the advantages herein set forth or departing from the scope of the appended claims.

I claim:

1. The combination with a heating furnace and a chain conveyer having spaced arms extending outwardly, for transporting articles therethrough, of an endless, metallic belt engaged by said arms and traveling therewith to support articles out of direct contact with said arms.

2. In a furnace for treating metallic sheets, the combination with a chain conveyer having flights spaced therealong, of an endless belt engaged by said flights for supporting sheets in the furnace out of contact with the flights.

3. A sheet treating furnace including an endless chain conveyer, and an endless, heat resisting, protective belt carried by said conveyer for supporting sheets in the furnace out of contact with the conveyer.

4. Means for protecting sheets from direct contact with a chain conveyer traversing a heat-treating furnace, comprising an endless, heat-resisting belt surrounding said conveyer and traveling therewith.

5. The combination with a plurality of chain conveyers traversing a heat-treating furnace and adapted to cooperate to pass articles therethrough, of a separate protective means for each of said conveyers comprising an endless belt therearound and traveling therewith.

10 In testimony whereof I have hereunto set my hand.

RAYMOND J. WEAN.
